(57) **CLAIM**

The ornamental design for a utility vehicle, as shown and described.

DESCRIPTION

FIG. 1 is a perspective view taken from a front, left side of a utility vehicle according to our design; FIG. 2 is a perspective view taken from a front, right side thereof;

FIG. 3 is a left side elevation view thereof;

FIG. 4 is a front elevation view thereof;

FIG. 5 is a right side elevation view thereof;

FIG. 6 is a rear elevation view thereof;

FIG. 7 is a top plan view thereof;

FIG. 8 is a bottom plan view thereof;

FIG. 9 is a perspective view taken from a rear, left side thereof; and,

FIG. 10 is perspective view taken from a rear, right side thereof.

Throughout the Figures, if and where shown: (i) the broken lines showing additional structure of the utility vehicle and/or its environment are for illustrative purposes only and form no part of the claimed design; (ii) the dotted/dashed lines adjacent shaded surfaces represent unclaimed boundaries of the claimed design; and (iii) the unshaded surfaces do not form part of the claimed design. Portions of the utility vehicle not shown in the Figures and not otherwise described in this specification do not form part of the claimed design.
